UNITED STATES PATENT OFFICE.

FERDINAND E. KLINE, OF CARBONDALE, ILLINOIS.

PORTABLE GARAGE.

1,318,769.

Specification of Letters Patent. Patented Oct. 14, 1919.

Application filed December 20, 1916. Serial No. 138,085.

To all whom it may concern:

Be it known that I, FERDINAND E. KLINE, a citizen of the United States, and a resident of Carbondale, in the county of Jackson and State of Illinois, have invented a certain new and useful Improvement in Portable Garages, of which the following is a specification.

The present invention relates to building construction, and has particular reference to garages of the portable or knock-down type.

It is an object of the present invention to provide a garage construction wherein the usual door trouble is eliminated.

Another aim of the present invention is to provide a construction of garage in which the same may be easily and quickly knocked down or set up, and which is economical to manufacture and transport from place to place.

The invention further aims at the provision of a combined garage and turn-table construction by means of which a vehicle may be entirely housed within the garage, and at the same time may be turned around to present either end of the vehicle to the door or outlet of the garage. This feature of the invention obviates the necessity of removing the vehicle from the garage and taking it to a suitable place to be turned around and subsequently backing the vehicle through the door opening in the garage.

The invention has for a still further object to provide improved means arranged within the garage to securely lock or anchor the vehicle thereto and to prevent theft, or unauthorized use of the vehicle.

The above, and various other objects and advantages of this invention will be more clearly brought out in the specific description of the present preferred embodiment thereof, the same being illustrated in the accompanying drawings wherein:

Figure 1 is a vertical central section taken through a portable or knock-down building constructed in accordance with the present invention, and being equipped with the improved turning means of this invention for supporting vehicles within the structure.

Fig. 2 is a similar view taken at right angles to the showing in Fig. 1 and disclosing the door mounting and construction.

Fig. 3 is a horizontal sectional view taken through the built-up structure.

Fig. 4 is a fragmentary, enlarged, sec-

tional view taken through one of the side walls of the building.

Fig. 5 is a detail enlarged sectional view taken through the upper edge of the building, showing the door mounting.

Fig. 6 is a detail enlarged sectional view taken through the lower corner of the building, showing the mounting of the lower ends of the doors thereon.

Fig. 7 is a detail perspective view of one of the bumpers employed on the turn-table, showing the locking means for securing the vehicle wheel against the bumper.

Fig. 8 is a detail sectional view of the upper corner of the building, showing the connection of the sectional roof through the sectional walls of the building.

Fig. 9 is a detail perspective view of one of the lug plates constituting the connection between the roof and the wall.

Fig. 10 is a detail view of the lower end of the door, showing the wedge blocks for binding the door against the side of the building.

Referring to these drawings, wherein like parts are designated by similar numerals of reference throughout the several views, the portable building is shown in the present instance as in the form of a garage adapted to house an automobile or the like. The building is made up of a number of arcuate sections each composed of top, bottom and intermediate curved ribs 15 of angle iron construction and held substantially in parallelism and in spaced-apart relation by connecting posts 16 which are also of angle iron construction and are suitably riveted or bolted to the opposite ends of the ribs 15. The ribs 15 are preferably secured with their horizontal flanges projecting inwardly, and have bolted, or otherwise suitably secured, against their outer faces attaching strips 17 which are preferably of wood or the like and into which may be driven nails. These attaching strips 17 are adapted to support an outer wall 18 of wood, metal or the like which is permanently secured to the strip 17, and which conforms to the curvature of the ribs 15.

The wall section thus formed has its end post 16 of angle iron construction and with their inwardly extending flanges located at the outer edges of the post 16 so that when a pair of the sections are assembled, the inwardly extending flanges thereof may be brought together and suitably secured.

Bolts 19 are detachably engaged through the inwardly extending flanges of the post 16 to clamp the same together, and any number of the bolts 19 may be employed for 5 securing the top, bottom and intermediate portions of the wall sections together. The wall 18 may be formed of weather-boarding with interfitting tongue-and-groove construction, of sheet metal, or any other material or composition from which the curved 10 walls of the section may be suitably formed.

Preferably, the building comprises six or more sections which are secured together in interlocking relation by means of the bolts 15 19. At one side of the building a door section is inserted, the same comprising opposed frame posts 20 joined at their upper ends by a top sill 21 which is suitably secured to the curved rib 22. The rib 22 is secured 20 to the upper ends of the angle iron post 16 which is adapted to abut the inturned flange of the post 16 of the adjacent section. The top sill 21 has secured to its outer side a track or rail 23 which extends entirely across 25 the sill 21 and extends at its opposite ends across the outer sides of the adjacent wall sections. One or more doors are suspended from the rail 23. In the present instance a pair of doors are disclosed. Each door 30 comprises a plurality of vertically extending strips 24 secured together by top and bottom corner irons 25 and 26, and are reinforced intermediate their ends by a transversely extending angle iron bar 27 secured across 35 the outer faces of the strips 24. Suitable hangers 28 are secured to the upper edges of the doors and engage the track 23 to support the doors and permit of the sliding movement of the same toward and from each 40 other.

As shown in Figs. 2 and 3 of the drawing, the inner adjacent ends of the bars 27 are provided with longitudinally extending lugs which form extensions of the horizontal 45 flanges of the bars 27, and which provide rigid hasp-members 29 which overlap when the doors are closed. A padlock 30 or the like is adapted for securing through the registering slots of the hasp-members 29 to 50 securely lock the doors in abutting relation. Lower track sections 31 are secured against the outer side of the opposite wall sections arranged adjacent to the doors. These lower track sections 31 comprise radially extending 55 bracket arms which carry upon their outer ends a vertical strip adapted for engagement against the outer faces of the doors adjacent to the lower edges of the same.

The inner adjacent ends of the track sections 60 31 are provided with binding or cam blocks 32 having inclined inner faces which slope outwardly from the door opening, and which coöperate with binding shoes 33 secured to the outer faces of the doors adjacent 65 to their remote ends. The shoes 33 are pro-

vided with outer inclined faces which are arranged opposite to the inner inclined faces of the blocks 32, and which are adapted for sliding engagement thereagainst to force the outer ends of the doors against the 70 adjacent side wall sections to form a close fit therewith.

A preferably cementitious floor or base 34 is provided for the building, and for the purpose of anchoring the sectional walls to the 75 base 34, a plurality of tie rods 35 are embedded in the cementitious base and have their outer ends offset upwardly and bolted or otherwise suitably secured to the horizontal flanges of the lowermost rib 15. The inner ends of the tie rods 35 are secured to a center plate 36 which is embedded in the base 34, and provided with an upwardly extending pivot post 37.

The anchoring plate 36 not only serves 85 the function of holding the tie rods 35 rigidly in the base 34 of the garage, but it also serves as a support for a turn-table which is arranged within the garage for supporting the car to permit of the turning 90 of the same into various positions without removing the car from structure. The turn-table comprises a pair of substantially parallel rails 38 having flaring downwardly inclined forward ends 39 adapted to receive 95 the wheels of the vehicle and guide the same into the channels of the rails 38. End braces 40 are secured between the rails 38, and each preferably comprises a pair of curved bars having their intermediate portions abutting and secured together, and having their diverging outer ends riveted or otherwise suitably secured to the ends 100 of the rails 38. The intermediate portions of the rails 38 are supported and braced by means of a transversely extending plate 41 which is secured at its opposite ends to the rails 38, and which has pivotal engagement 105 at its intermediate portion upon the upwardly extending post 37. This strip or plate 41 is of sufficient strength to support 110 and guide the turn-table about the post 37. The rollers 38 are provided, adjacent to their opposite ends, and at their outer sides, with bearing brackets 42 which carry rollers 115 43 therein for engagement with the floor 34 to support the turn-table clear of the floor and permit of the relatively easy rotation 120 of the same. The post 37 is provided, at a point above the anchoring plate 36, with a bearing plate 44 which is partly sunk into the upper surface of the base 34 and which is of sufficient thickness to engage the underside of the intermediate base 41 to support 125 the latter and the intermediate portions of the rails 38 in spaced relation above the floor of the garage.

The inner ends of the rails 38, or the ends opposite to the flaring portions 39, are provided with detachable bumpers or retaining 130

members 45 which are in the form of shells conforming to the transverse and circumferential curvature of the wheels of the vehicle, and which are of sufficient length to engage and support the wheels from further movement. The bumpers 45 are provided with pairs of arms 46 adapted to engage in the inner ends of the rails 38, and are detachably secured in such position by means 10 of removable bolts or pins 47 which engage with the lateral upstanding flanges of the rails 38.

Each bumper 45 may be provided at one side with a hinged hasp bar 48 of such 15 length and curvature as to be swung inwardly between the spokes of a wheel and support the inner side of the rim thereof. The opposite side of each bumper 45 is provided with a staple 49 adapted to receive 20 the flattened extremity of the hasp bar 48 and to also receive a padlock or the like for locking the bar 48 through the wheel. This hasp bar 48 is adapted to lock the wheel to the bumper and prevent the unauthorized removal of the vehicle from the 25 garage. It will be noted that the attaching arms 46 of the bumpers are of such length that the retaining bolts 47 are located in such position that the lower portions 30 of the wheels of the vehicle engaging the bumpers fit between the bolts and prevent the removal thereof from the arms 46 and the adjacent portions of the flanges of the rails. Thus, the vehicle is securely 35 locked not only to the bumpers 45, but also to the rails 38. The bumpers cannot be removed until the vehicle is moved to a slight extent to free the bolts 47.

The portable structure is provided with a 40 detachable roof which is preferably made in sections corresponding in number to the sections of the wall. In the present instance the roof is disclosed as being composed of six sections. Each section of the roof is provided 45 with end rafters 50 and intermediate ribs or rafters 51 which radiate from the inner raised end of the roof section. The end rafters 50 are of angle-iron formation and have the flanges thereof directed inwardly and so arranged as to abut against the flanges of the adjacent roof section, and to be secured thereto by means of bolts 52 or the like for detachably uniting the sections of the roof. Preferably, the roof is of 50 conical form and the rafters 50 and 51 diverge from the apex of the roof to the eaves thereof. Attaching lugs 53, of angle-iron formation, detachably secure the rafters 50 and 51 to the upper horizontal flanges of the 55 ribs 15 of the side walls. A suitable metallic or other roof covering 54 is secured to the rafters 50 and 51 and are adapted to overlap or otherwise meet to provide a water-tight covering for the roof.

From the above description it will be 65 readily understood that the structure may be knocked down by the removal of the bolts 52 and the disengagement of the lugs 53 from the rafters 50 and 51 to remove the roof and permit of the packing of the sections thereof into relatively small space. It will also be noted that by the removal of the bolts 19 the wall sections may be separated and packed into convenient form.

When the garage is set up, the bottom or 75 base 34 may have embedded therein the tie-rods 35 and the anchoring plate 36. This structure holds the side walls rigidly to the base and prevents the accidental lateral displacement of the structure from the base. 80 The anchoring plate 36 also serves as a substantial support, braced by the tie rods 35, to hold the turn-table which is mounted centrally in the structure and upon which the vehicle or the like is positioned when in the 85 structure. The rollers 43 permit of the ready turning of the vehicle into various angles or positions within the structure and permit of a driver driving the car, front end foremost, into the garage in the usual manner. The car may then be turned around and driven, front end foremost outwardly through the open side of the structure. The doors 27 may be slid upon the rails 23 and 31 away from each other and against the 90 outer sides of the adjacent wall sections to permit of the free entrance and egress of the vehicle. When the doors are closed the same are brought together and the lugs 95 29 are overlapped to register the slots thereof and permit the securement of the padlock 30 through the lugs to hold the doors together. If desired, a foot-bolt 55 may be 100 employed at the bottom of one of the doors to securely hold the meeting ends thereof from swinging laterally, and to hold the doors from being forced in one direction past the door opening. Wedge blocks 33 of the doors, however, assist the bolts 55 as the blocks bind against the stationary blocks 32 105 and securely hold the outer ends of the doors against the adjacent side sections.

It is of course understood that various changes and modifications may be made in the above-specifically described construction 115 of portable building without departing from the spirit of this invention, and being restricted only by the scope of the following claims.

I claim:

1. In a garage for vehicles, the combination of a housing circular in plan, and of an internal diameter to accommodate the vehicle over all and a turn table centrally disposed in said housing of a size to accommodate the wheel base of the vehicle.
2. In a garage for vehicles, the combination of a housing provided with a door way,

10 and a turntable in said housing provided with guide rails, for the wheels of the vehicle, the guide rails being adapted to be adjusted adjacent to and in alinement with 5 the jambs of said doorway.

15 3. In a garage for vehicles, the combination of a housing provided with a door way, and a turntable in said housing provided with guide rails for the wheels of the vehicle, 10 said guide rails having outwardly flaring end portions adapted to be adjusted by the turning of the turntable into position adjacent to and in substantial alinement with the jambs of the doorway.

20 4. In a garage for vehicles, the combination of a housing circular in plan and of an internal diameter to accommodate the vehicle over all, a turntable centrally disposed in said housing of a size to accommodate 25 the wheel base of the vehicle, and bumpers on said turntable to limit the movement of the vehicle toward the wall of the housing.

25 5. In a garage for vehicles, the combination of a housing circular in plan and of an internal diameter to accommodate the vehicle over all, a turntable centrally disposed in said housing and of a size to accommodate the wheel base of the vehicle, and removable bumpers on said turntable to 30 limit the movement of the vehicle toward the wall of said housing.

35 6. The combination with a garage, of a turntable arranged therein and having a center pivot pin upon which the turntable is adapted to rotate, a cementitious base for supporting the garage and in which the lower end of the pivot pin is embedded, and tie rods embedded in the cementitious base and secured at one end to the pivot pin and 40 at other ends to the garage for holding the turntable from displacement relative to the garage and for anchoring the pivot pin and the garage to the base.

45 7. In a garage for vehicles, the combination of an inclosing wall, a base for said wall, tie-rods carried by said base and adapted for securing at their outer ends to said wall for holding the same from lateral displacement from the base, an anchoring plate secured to the inner ends of said tie-rods and adapted for securing to said base, and a turntable mounted on said anchoring plate for movement within said wall.

55 8. In a garage for vehicles, the combination of an inclosing wall, a cementitious base adapted to support said wall, a plurality of tie-rods embedded in said cementitious base and adapted for securing at their outer ends to said wall to hold the latter from lateral displacement from the base, an anchoring plate embedded in said base and having connection with the inner ends of said tie-rods, a post projecting upwardly from said anchoring plate, and a turn-table pivotally

60 mounted on said post whereby said anchoring plate is adapted to support said turntable and to hold said tie-rods and said wall from displacement.

65 9. In a garage for vehicles, the combination of an inclosing wall, a cementitious base 70 for supporting said wall, tie-rods embedded in said base and having securing to said wall to hold the same from displacement from the base, an anchoring plate embedded in said base and provided with an upwardly 75 extending post projecting above the base, said plate being adapted for securing to the inner ends of said tie-rods to hold the same from displacement, a brace pivotally mounted upon the upper end of said post, a pair of substantially parallel rails secured to the outer ends of said brace, rollers for supporting the outer ends of said rails, and outer braces connecting said rails to hold the same together for pivotal movement about 80 said post.

85 10. In a portable garage, the combination of an inclosing wall, a cementitious base supporting said wall, an anchoring structure embedded in said base and having engagement with said wall to hold the same from displacement, said anchoring structure being provided with an upwardly extending post projecting above the base, a brace pivotally mounted intermediate its 90 ends upon said post, a pair of rails secured intermediate their ends to the extremities of said brace, rollers supporting the outer ends of said rails, outer braces connecting the outer ends of said rails to hold the same in 95 substantially parallel relation, the forward ends of said rails being flared and adapted to receive the wheels of a vehicle to guide the same onto said rails, and bumpers secured to the opposite ends of said rails to 100 prevent the movement of the vehicle from the rails.

105 11. In a garage, an inclosing wall, a base for the wall, an anchoring structure carried by the base and engaging the wall to hold 110 it from displacement, a turn-table mounted on said reinforcing structure and adapted to turn within the wall, said turn-table comprising a pair of substantially parallel rails adapted to receive the wheels of the vehicle, 115 and a pair of detachable bumpers carried upon the inner ends of said rails to engage said wheels and hold the vehicle from movement from the inner ends of the rails.

120 12. In a garage, an inclosing wall, a base supporting said wall, an anchoring structure carried by said base and engaging said wall, a turn-table mounted on said anchoring structure and adapted to turn within the wall, said turn-table comprising spaced- 125 apart rails adapted to receive the wheels of a vehicle and being flared at one end to guide the wheels on the rails, a pair of

bumpers mounted upon the opposite ends of said rails, means for detachably securing said bumpers to the rails, and means for locking the vehicle wheels against the bumpers to prevent the unauthorized removal of the vehicle from the garage.

13. In a device as specified, the combination of an inclosing structure, a base supporting said structure, a turn-table mounted 10 on said base within the structure, a pair of

bumpers detachably mounted on said turn-table adapted to receive vehicle wheels thereagainst, hasp bars pivotally mounted upon one side of the bumpers and adapted for engagement through the wheels, and 15 means for locking said bars in the latter position to secure the wheels to the bumpers and prevent the removal of the vehicle from the turn-table.

FERDINAND E. KLINE.
